UNITED STATES PATENT OFFICE.

BURKE BRADBURY, OF SCHENECTADY, NEW YORK, ASSIGNOR TO GENERAL ELECTRIC COMPANY, A CORPORATION OF NEW YORK.

TRANSFORMER.

Application filed March 27, 1922. Serial No. 547,001.

My present invention relates to high frequency transformers and more particularly to so-called "intervalve" transformers for connecting together successive stages of high frequency vacuum tube amplifiers.

The object of my invention is to provide a transformer which will be efficient in operation over a wide range of frequencies or wave lengths.

10 The novel features which I believe to be characteristic of my invention are set forth with particularity in the appended claims. My invention itself, however, both as to its organization and method of operation will 15 best be understood by reference to the following description taken in connection with the accompanying drawing in which Fig. 1 is an elevation of one of my devices; Fig. 2 is a vertical cross-section; Fig. 3 is an elevation of one-half of a transformer showing the interior construction; and Fig. 4 shows 20 a circuit arrangement in which my transformer may be employed.

As shown in the drawing, the transformer 25 comprises a pair of similar coils 1 and 2 separated by a thin sheet 3 of insulating material. The coils 1 and 2 surround an open core 4 made up of thin laminations of enameled iron preferably having a thickness of one and one-half mils or less. The coils are enclosed in a casing of insulating material made up of two similar parts 5 and 6 which may be fastened together by means of the screw bolts 7 and 8 which also may 30 serve for securing to the casing the supporting legs 9 and 10. Each coil is provided with end terminals 11 and 12, and an intermediate terminal 13. Switches 14 and 15 which are mounted on the casing permit of 35 the short circuiting of the portions of the coils between terminals 12 and 13.

In the circuit arrangement shown in Fig. 4, high frequency currents to be amplified are impressed from the antenna 16 upon the input circuit of a three-electrode vacuum tube amplifier 17. The coil 1 is included in the output circuit of amplifier 17 and the coil 2 is included in the input circuit of a second amplifier 18. As many amplifier 40 stages as desired may be connected up in this way and the transformer in the output circuit of the last amplifier of the series may be connected to a detector of any form desired.

In the construction of radio frequency

transformers in the past the usual practice has been to reduce to a minimum practical value the capacity between turns of the winding. This has resulted in transformers which were efficient over a very narrow 60 range of wave lengths and the efficiency of which dropped off rapidly on either side of this range. I have found however that by making the capacity between turns as high as practical a transformer will be obtained 65 which is efficient over a much wider range of wave lengths and one, the efficiency of which does not fall off so rapidly over either side of the most efficient range. In order to give the coils as high capacity as 70 possible I employ as thin insulation as possible to secure the necessary insulation between turns, and arrange the winding in compact form. The capacity may be further increased by impregnating the coil with 75 insulating material such as a wax having a high dielectric constant.

I have also found that the use of a core of thin magnetic material such as I have described, greatly increases the range of 80 wave lengths over which the transformer operates efficiently. For short wave lengths over a range which may extend from 200 to 1500 meters the magnetic skin effect is so great that the iron has practically no 85 effect upon the operation of the device. At longer wave lengths the magnetic skin effect decreases and the iron becomes more effective causing a gradual increase in the inductance of the coils as the wave length increases. 90 This results in broadening the tuning of the coils and hence renders the transformer efficient over a greater range of wave lengths than one which has coils with sharp tuning characteristics. 95

In the operation of my transformers over a range of wave lengths from 200 to 500 meters the switches 14 and 15 are closed so that the sections of both coils connected thereto are short circuited while over the 100 range from 500 to 5000 meters the switches 14 and 15 are opened so that the full windings of both primary and secondary coils are used. This short circuiting is not detrimental to the operation of the transformer, since the number of turns short circuited is such that their impedance is very high for the frequencies used with this condition. On the contrary this seems to be an advantage as I have found that it permits of the use 110

of a coil of a greater number of turns than would ordinarily be employed for short waves and it is only by the use of such a coil that the desired broadening of the tuning can be obtained. The use of single coils with comparatively few turns without taps will give efficient operation over a very narrow range of wave lengths but inefficient operation for all other wave lengths. By 10 short circuiting the unused turns much more efficient operation is obtained than if these turns were open circuited as in the latter case the open circuited turns would tune with the capacity between turns and cause high losses whereas the short circuiting switches short circuit the capacity between turns and produce a high impedance circuit.

I construct my transformers with a one to one ratio because of the fact that with 20 the usual amplifying tubes the internal capacity between elements is so great that the impedance of the input circuit of one tube is of about the same order of magnitude as the impedance of the output circuit of the 25 preceding tube. Furthermore, it appears that for short wave lengths the natural period of the coils should be in the neighborhood of the frequencies used. If a step-up ratio were employed the primary and secondary windings would have different natural periods and this would result in less transfer of energy from one tube to the next.

To enable one to successfully practice my 35 invention the following example is given of the physical characteristics of a transformer which I have used extensively in carrying my invention into effect. The two coils are each wound with about 465 turns of five mil single silk insulated and enameled wire. 40 The total resistance of each coil is about 70 ohms and the resistance of the portion used for short waves is about 20 ohms. The internal diameter of the coils is about $\frac{7}{8}$ " and external diameter about $1\frac{1}{2}$ " and the coils 45 are about $\frac{3}{2}$ " long. The core is 1" long and has a cross section of about $\frac{1}{4}$ sq. in.

A transformer constructed as I have described has an efficiency of transformation as determined by audibility amplification 50 measurements over a range of wave lengths from two hundred to about fifteen hundred meters at least as high as that of a similar transformer without the iron core while over a range of wave lengths from about fifteen 55 hundred to five thousand or above the efficiency is higher than that of a similar transformer without an iron core. Below about

five hundred meters the transformer operates at highest efficiency with the switches 14 and 15 closed while above that wave 60 length it operates with higher efficiency with these switches open.

What I claim as new and desire to secure by Letters Patent of the United States, 65 is:—

1. A radio frequency transformer comprising a pair of coils having similar characteristics in close proximity to each other, said coils having appreciable capacity between turns, an open core for said coils made up of thin laminations of magnetic material, a casing for said coils and switches mounted on such casing, said switches being connected to suitable taps on said coils for short circuiting such portion of the turns 75 thereof that the impedance of the portion to be short circuited will be greater than that of the remaining portion.

2. A radio frequency transformer comprising a pair of coils having similar characteristics, said coils having appreciable capacity between turns, an open core for said coils made up of thin laminations of magnetic material and means for short circuiting such portions of each of said coils that 85 the impedance of the portions to be short circuited will be greater than that of the remaining portions.

3. A radio frequency transformer comprising a pair of coils having similar characteristics; said coils having appreciable capacity between turns, an open core for said coils made up of thin laminations of magnetic material and means for short circuiting such portions of each of said coils that 95 the impedance of the portions to be short circuited will be greater than that of the remaining portions, the efficiency of transformation of said transformer below a wave length of about five hundred meters being 100 greater with such portions of the coils short circuited and above such wave length being greater with the entire coils in circuit.

4. A radio transformer comprising a pair of coils having similar characteristics, said coils having an appreciable capacity between turns, an open core for said coils made up of thin laminations of magnetic material, a casing enclosing said coils, and switching means mounted on the casing and adapted 105 to short circuit portions of said coils.

In witness whereof, I have hereunto set my hand this 25th day of March, 1922.

BURKE BRADBURY.
